UNITED STATES PATENT OFFICE.

JOHN R. RUDE AND HORACE G. SWOPE, OF LIBERTY, INDIANA, ASSIGNEES TO THE RUDE BROTHERS MANUFACTURING COMPANY, OF SAME PLACE.

GRAIN-DRILL.

SPECIFICATION forming part of Letters Patent No. 276,474, dated April 24, 1883.

Application filed October 17, 1882. (No model.)

To all whom it may concern:

Be it known that we, JOHN R. RUDE and HORACE G. SWOPE, of Liberty, Union county, Indiana, have invented certain new and useful Improvements in Grain-Drills, of which the following is a specification.

This invention relates to the arrangement of the seat and drag-lifts of common grain-drills, as hereinafter set forth.

10 In the accompanying drawings, Figure 1 is a side view, part section, of a grain-drill embodying our improvements; and Fig. 2 is a rear elevation of some of the parts in position.

15 A represent the end pieces of the main frame; B, the front rail of the main frame; D, the seed-box; E, the lift-bar; F, the lift-bar lever; G, the drag-chains; H, the drag-bars; I, the boots; J, the pivot-lugs cast on the boots; K, the break-pins in the lugs J; L, 20 the axle, all constructed and arranged as usual in grain-drills.

Q is a lever, double-ended, as shown, located between the two bars usually forming the drag-bar H. One end of the lever bears on the lug J of the boot I and the other end of the lever receives the chain G, which is usually attached directly to the drag-bars. When the chains are taut and the boots lifted the short ends of levers Q bear firmly on lugs J of the 25 boots and prevent the boots from tipping out of position, as is usually the case unless a second break-pin is used under the drag-bar for each boot. If, in backing, the boots strike obstructions, they yield by lifting their drag-bars 30 and oscillating their levers Q slightly in an obvious manner.

R are levers pivoted to the rear of the main frame.

V is a board attached to the levers R and 40 supported by them, the ends of the board entering into shallow mortises in the inner faces of the levers.

W is a truss-rod reaching from lever to lever, and trussed by the strut-casting X, under the 45 center of the board V, and by the nuts Z, outside the levers R.

T is a seat bolted to top of board V by the same bolts, Y, which hold the strut-casting X. Lugs S, catching under the frame to which the 50 levers R are pivoted, prevent the seat dropping.

U is a hook-catch upon the rear face of the seed-box. It engages with the seat, when the seat, with board and levers, is turned upward, and retains it out of the way while the boots, &c., are being inspected or manipulated. The position of the lever F is such that a seat, located in the rear of the seed-box, gives the driver good control of the lever. The board V, reaching from lever to lever, produces a simple spring for the seat.

C is a rail reaching from end to end of the main frame and firmly attached to the end pieces of the frame. To it are attached two foot-rests, P, for the use of the driver. The foot-rests are pivoted to the rail at O, and are adapted to swing backward when an obstruction is met. Each foot-rest is retained in its normal position by a break-pin, N, in a staple in the rail C, straddled by a notched arm cast on the shank of the foot-rest. The foot-rests project down between drag-bars without interfering with them.

We claim as our invention—

1. The lever Q, combined with the lift-chain, drag-bar, and boot, substantially as set forth.

2. The seat T in the rear of the machine, combined with foot-rests P, attached to the frame of the machine, between the drag-bars, substantially as set forth.

3. The seat T, in the rear of the machine, combined with foot-rests P, hung on pivots and arranged between the drag-bars, substantially as set forth.

4. The combination of the machine-frame, the arms or levers R, pivoted thereto, the seat T, and the wooden board V, supporting the seat, and bolted to said arms or levers, substantially as set forth.

5. The seat T, combined with the wooden board V, rod W, and strut X, substantially as set forth.

6. The seat T, combined with wooden board V, rod W, strut X, and levers R, receiving the ends of the board and rod, substantially as set forth.

JOHN R. RUDE.
HORACE G. SWOPE.
